UNITED STATES PATENT OFFICE

JAMES M. GARVEY, OF NEW YORK, N. Y., ASSIGNOR TO THE AMERICAN LAUNDRY MACHINERY COMPANY, OF CINCINNATI, OHIO, A CORPORATION OF OHIO

LAUNDRY-MARKING TAG

Application filed August 24, 1927. Serial No. 215,155.

This invention relates to identifying apparatus and particularly to markers for use with suitable racks for receiving like markers.

More specifically, the invention relates to means for attaching the marker to the article and for facilitating the removal thereof.

In the specific embodiment shown the marker comprises a main body portion which 10 may be provided with any suitable identifying numbers or other indications and a physical identifying means such as a suitably shaped opening for engagement with a properly shaped bar or rack. The marker also 15 includes a shank to be applied to the goods and it is provided with suitable openings for receiving staples adapted to be passed through the openings and through the article and bent up under the article with the ends 20 of the prongs embedded in the fabric of the article to hold it firmly in place. The marker may also be provided with a recess or opening in its shank below the cross member of the staple to facilitate the application of a 25 removing tool in the removal of the marker. This recess may be in the form of a perforation or slot extending completely through the shank and not only facilitating the removal of the staple and the marker from the 30 article, but also providing a space for the reception of the bent up ends of the prongs of the staple to increase the hold thereof upon the article.

Other features of the invention will be 35 obvious from the following description, drawings and claims.

Referring to the drawings, Fig. 1 is a perspective view of one form of marker; Fig. 2 is a similar view showing the recess but 40 with a different type of opening for engaging the bar and rack; Fig. 3 shows the marker illustrated in Fig. 1 applied to the article; Fig. 4 is a section through the article and through the marker shank showing the opening 45 for the staple and also showing the staple; Fig. 5 is a similar view with the staple applied; and Fig. 6 shows the staple and article together in side elevation; Fig. 7 is a modified form of staple opening; Fig. 8 50 shows the form shown in Fig. 7 applied to the

article; Fig. 9 shows another modified form of marker wherein the recess in the shank for the removal of the staple is made in the form of a slot which also assists cleansing a water ventilation of the article; Fig. 10 shows the 55 form shown in Fig. 9 applied to an article with transverse stapling; Fig. 11 shows the same type of marker with another form of stapling; and Fig. 12 shows the tool used for removal of the staple.

In the embodiment shown, 1 represents the main body portion provided with a suitably shaped opening 2 for engaging a suitable rack or bar for supporting markers belonging to one group for the same size and shape of 60 opening. Markers belonging to another group may have a modified form of opening, as shown at 3 in Fig. 2. The shank 4 of the marker shown in Figs. 1 and 3 is provided with suitably spaced openings 5 for 65 the reception of a staple 6 shown in Fig. 4. In the arrangement shown in Fig. 2 the shank is also provided with a recess 7 immediately below the connecting portion of the staple 70 whereby a tool may be inserted below this portion of the staple in removal, as will appear. The recess 7 in the shank extends from a point within the shank out through the end in curved formation and does not project 75 through the stock of the shank.

In the arrangement shown in Fig. 7 the shank is provided with a circular opening 7 extending through the shank within the 80 staple openings.

In Fig. 9 the shank is provided with a rectangular slot 7" extending out through the end of the shank and between the groups of 85 staple openings.

By reference to Fig. 9 it will be seen that by any suitable means the staple 6 may have 90 its side prongs inserted through the openings 5 through the article and may then be bent up under the article with the inner ends shown at 8 embedded into the article.

What I claim is:

1. An identifier comprising an identifier body portion and a shank provided with spaced staple openings and a recess in the shank between said staple openings adapted to be bridged by the cross member of the 100

staple and to receive an implement for removing the staple.

2. An identifier as in claim 1 wherein the recess in the shank extends from a point between the staple openings to the center end of the shank.

JAMES M. GARVEY.
